United States Patent Office

Des. 196,852
Patented Nov. 12, 1963

196,852

NAUTICAL HOOK

Irving Oldak, Lynbrook, N.Y., assignor to His Lordship
Products Company, New York, N.Y., a partnership

Filed Feb. 5, 1963, Ser. No. 73,453

Term of patent 3½ years

(Cl. D41—1)

FIG. 1 is a side elevational view of a nautical hook showing my new design, the cord to which it is attached by means of an end knot being shown in broken lines for illustrative purposes only;

FIGS. 2, 3, 4, 5 and 6 are front, rear, opposite side, top and bottom views, respectively, thereof, and

FIG. 7 is a sectional view taken substantially on line 7—7 in FIG. 1.

I claim:

The ornamental design for a nautical hook, as shown and described.
